UNITED STATES PATENT OFFICE

FRANS G. AGRELL, OF STOCKHOLM, SWEDEN.

SELECTING DEVICE.

979,404.

Specification of Letters Patent. Patented Dec. 27, 1910.

Application filed February 27, 1907. Serial No. 359,661.

To all whom it may concern:

Be it known that I, FRANS GUNNAR AGRELL, a subject of the King of Sweden, and resident of Stockholm, Sweden, have invented 5 certain new and useful Improvements in Selecting Devices, of which the following is a specification.

This invention relates to selecting devices and more particularly to that class of selecting devices adapted for use with electrical 10 circuits where the selection is performed by the coöperation of electro-magnets.

One object of my invention is to provide a large number of possible connections with 15 a small number of contacts in a simple device. I accomplish this by means of a peculiar arrangement of armatures and co-operating electro-magnets or relays. In the selecting device as herein shown and described 20 the coöperating armatures of four electro-magnets act to move a member into operative position with relation to any other member of a group, the movement of said member being dependent upon the positions 25 of the armatures of said electro-magnets. Three of the electro-magnets are placed in a triangular position and said first named member is connected to the three armatures by means of universal joints in the corners of 30 said triangle so that the member can swing around several axes passing through these universal joints. As will be described later, seven different positions of this member can be obtained by means of these three electro- 35 magnets and the introduction of a fourth electro-magnet enables me to increase said number to fourteen.

A further object of my invention is to provide a selecting device that will engage 40 the desired member without first sweeping over or engaging any others.

The advantages of a device of this kind are evident. It is possible to select and make any one of fourteen connections by 45 means of one impulse and by repetition of the impulses an almost unlimited number of connections can be selected without difficulty.

The device has been designed especially 50 for use in automatic telephone systems but is equally well adapted for typewriter telegraphs and similar uses. In the following specification describing the accompanying drawings I have shown one embodiment of 55 my invention in a preferred construction for telephone use.

In the accompanying drawings like parts have been given similar reference numbers in the different views.

Figure 1 is a perspective view of a simple 60 form of device employing three fundamental relays and armatures and a contact maker. Fig. 2 is a top plan view of a device with an increased number of contacts showing the contact maker and the contacts. 65 Fig. 3 is a plan view of the device with the top removed on the line 3—3 in Fig. 4. Fig. 4 is a sectional side elevation substantially on line 4—4 in Fig. 3.

Referring now to Fig. 1, 5^A, 5^B and 5^C are 70 the three relay coils and 6^A, 6^B and 6^C are their corresponding armatures which may be pivoted at 13, to suitable supports. The armatures have spherical projections 11 which carry the triangular support 3. This support carries a rod 4, which in its turn carries the contact member 7. At 1^A to 1^F are 75 represented the six fundamental contacts and 2 is another contact adapted to be engaged by the lower end of the rod 4. The 80 contact member and its supporting parts are represented in their position of rest, that is, when no relay is operated. In this position the member 7 is making no contact. If now one of the relays, for instance 5^A, operates 85 and attracts its armature 6^A the point 11^A will be lowered and as a result the triangular support 3 will swing around an axis that passes through 11^B and 11^C. The rod 4 and the contact star 7 will now move toward and 90 make contact with the contact spring 1^A, giving us the first combination. When the current ceases to flow in relay 5^A its armature is restored to its position of rest by means of a suitable spring not shown in this figure. If 95 now relay 5^B operates the triangle 3 will swing around an axis passing through 11^A and 11^C and contact will be made between the star 7 and the spring 1^B. If, instead, relay 11^C should operate the triangle will 100 swing around an axis passing through 11^A and 11^B and the star will make contact with spring 1^C in a like manner. If relays 5^A and 5^B are energized simultaneously the triangle will swing around an axis passing through 11^C and parallel with a line through 105 11^A and 11^B. The star will now make contact with the contact spring 1^B when 5^A and 5^C are energized simultaneously and with contact spring 1^D when 5^B and 5^C are energized simultaneously. If all three relays 110 are energized at the same time the rod 4 will 113

retain its vertical position but will be lowered and make contact with the contact spring 2. These seven connections are all that can be obtained with a combination of 5 three ordinary relays.

In the embodiment of my invention as shown in Figs. 2, 3 and 4, I have added another relay which when operated turns the contact star sufficiently so that it when swung 10 about its axis as described will engage another set of seven contacts, which contacts are marked 8. In order to accomplish this result the rod 4 carrying the star 7 is mounted so that it can turn in relation to the 15 triangular support 3. It is, of course, possible to effect the change of the relative position of the contact member in other ways, which it is not necessary to describe here as any such modifications of my invention are 20 matters of design.

Referring now to Figs. 2, 3 and 4, 14 is a base upon which the device is mounted. The base carries three columns 15 which in turn carry a plate 16 that is used as a yoke for 25 the cores 17 of the relay coils 5. It also carries an insulated member 18 upon which the contacts 1, 8 and 10 are mounted. Upon the base plate are mounted other columns 19, carrying screw pivots 20 for the relay armatures 21. Normally these armatures rest against pins 22 in such a position that the same will be operated by the cores 17 of the relays 5 when energized. The armatures 21 are so positioned in relation to each other 30 that the ends 23 lie in the corners of a regular triangle and the star shaped member 3 is connected to the armatures at said points by means of universal joints 24, which in the drawings are shown as adjustable screws 40 with spherical ends 11 which rest in spherical recesses of said armatures. The member 3 carries a tube or bushing 25 surrounding the rod 4, which carries the star shaped contact member 7. The rod can be turned 45 in said bushing and kept in its vertical position by means of the collars 26 and 27, secured to rod. The ring 26 carries a pin 28, the object of which will be explained later. Upon the base is mounted another relay 29 50 which has an armature 30 pivotally mounted between two columns 31. Said armature engages a rod 32 which is slidably mounted in the columns 15 and 33 and held in its normal position of rest as shown in the drawings by means of the spring 34, in which position it holds the relay armature 30 away from its core. The other end of said rod is formed in such a way that it engages the pin 28. If the relay 29 operates its armature 60 will be attracted and the rod 32 moved in toward the center, thus turning the rod 4 and its contact star 7 by means of the pin 28, as before described in connection with Figs. 1 and 2.

65 The operation of the device as shown in

Figs. 2, 3 and 4 is similar to that shown in Fig. 1 and it only remains to mention that the contact 2 in Fig. 1 corresponds to the contact 9 and that the relay armatures 6 in Fig. 1 correspond to the relay armatures 21 75 in these figures. It will also be noted that these armatures move upward instead of downward as in Fig. 1 so that the contact member 7 will be raised instead of lowered when all three fundamental relays 5 operate, 75 thus making contact with 9 if relay 29 does not operate and with contact 10 if it does operate.

As many changes could be made in the above construction and many apparently 80 widely different embodiments of my invention designed without departing from the scope thereof, I intend that all matter contained in the above description or shown in the accompanying drawing shall be interpreted as illustrative merely of an operative embodiment of my invention and not in a limiting sense.

What I claim is:

1. In a selecting device, in combination, 90 a group of members each adapted to be rendered operative by another member, a member pivotally mounted upon the armatures of electro-magnets and adapted to swing about said pivots, a plurality of electro-magnets 95 each provided with an armature forming a pivotal support for said member, any one of said electro-magnets being adapted to operate its armature and to swing said member about the pivotal support of another 100 armature causing said member to render any of the members of said group operative.

2. In a selecting device, in combination, 105 a plurality of contacts, a member pivotally mounted upon the armatures of electro-magnets and adapted to turn about said pivots, a plurality of electro-magnets each provided with an armature forming a pivotal support for said member, any one of said electro-magnets being adapted to operate its armature and to turn said member about the pivotal support of another armature causing 110 said member to engage one of said contacts, and means for operating said device.

3. In a selecting device, in combination, 115 a number of electro-magnets, armatures operated by said electro-magnets, three of said armatures being so positioned that corresponding points upon said armatures form a triangle, a member attached to said armatures so that it may swing about any one of several axes passing through said points, said members being adapted to engage a contact when swung about an axis, and contacts adapted to be engaged by said member. 120

4. In a selecting device, in combination, 125 four electro-magnets, armatures operated by said electro-magnets, armatures of three of said electro-magnets being so positioned that corresponding points upon said armatures 130

form a triangle, a member attached to said armatures so that it may swing about any one of several axes passing through said points, a contact making member mounted 5 so as to take several different positions with relation to said first named member, a plurality of sets of contacts each set adapted to be engaged by said contact making member in each of its said positions, and a fourth 10 electro-magnet having an armature adapted to change the relative positions of said members when operated.

5. In a selecting device, in combination, a number of electro-magnets, armatures operated by said electro-magnets, a member supported at three points so that it may swing around any one of several axes passing through said points of support by the 15 movement of said armatures, a contact making member attached to said first named 20

member so that it may take several positions with relation to a number of groups of contacts, a number of groups of contacts, each contact in a group being adapted to be engaged by the contact making member when the first named member is swung around a certain axis, and an electro-magnet adapted to change the relative positions of the contact making member when the first named member is swung around a certain axis and an electro-magnet adapted to change the 25 relative positions of the contact making member and the group of contacts. 30

Signed at New York in the county of New York and State of New York this 11th 25 day of Feb. A. D. 1907.
